PNEUMATICALLY ACTUATED VENEER CLIPPER

Donald C. Porter, Tacoma, Wash.

Application June 19, 1948, Serial No. 33,953

23 Claims. (Cl. 164—42)

1

This invention relates to a pneumatically actuated veneer clipper.

More particularly my invention relates to a pneumatic actuating sheet material clipper and feed control mechanism for said sheet material.

For clearness and definiteness of illustration, I will describe my invention as applied to veneer clipper mechanism, but it is to be understood that my invention is not to be restricted to any such definite or specific application but is applicable to uses where similar conditions exist, in whole or in part, such as in the metal art, plastic art, and synthetic board art.

In plywood manufacturing plants, the veneer used in making the plywood is peeled from logs in a sheet by a veneer lathe being rotary cut and goes to a clipper by which the sheet is cut into strips or panels of predetermined, varying, or uniform dimensions. The sheet of veneer as it comes from the lathe has numerous defects, such as knots, pitch pocket holes, decayed spots, and the like. These defects make it necessary in the interest of conserving wood and utilizing the same to the best possible advantage, to remove such defects by clipping out sections of the sheet. Thus, strips are provided of widths of different sizes so that parts with the worst defects can be discarded and parts with lesser defects or no defects can be put to different uses, such as for core stock and for different grades of face stock.

In the manufacture of plywood panels (that is, the assembly of veneer pieces), the veneer or plywood laminae, as rotary cut, from the peeler log is conveyed from the peeling mechanism by a suitable conveyor means, as belts, at a fairly high speed for efficient production. This requires that the clipper should be capable of controlled high-speed operation so that the sheet of veneer can be cut up into even relatively narrow strips (thus requiring many clipping operations) if the character of the veneer so requires without substantially interrupting the continuous flow of the veneer along the production line.

In clipper mechanism as heretofore commonly employed for veneer manufacture, a very serious objection obtains to the great vibration induced by the operation of the clipper. The clipper mechanism, as heretofore provided and commonly used, is of a complex character involving a great number of moving parts which, under strenuous operation, requires to be overhauled frequently and continuous maintenance. Overhauling often is required weekly. A primary object of my invention is to provide a knife assembly in a clipper mechanism with only one mov-

2

ing rigid mechanical part. Also, my purpose is to reduce the lubricating problem so that the mechanism may operate long periods of the order of weeks and even months without lubricating.

5 A primary object of my invention is to reduce the vibration to a minimum to reduce wear to provide precision operation and to reduce maintenance expense.

10 A further primary object of my invention is to provide a clipper mechanism which will conserve plywood and thereby avoid wastage of one of our great national resources, our forests, as well as to provide economical manufacture.

15 In using pneumatic pressure as actuating high-speed means for operating mechanism not only in the veneer art but in other arts, definite problems arise particularly where high speed and uniform pressure is involved. With piston and toggle connecting means, equal pressure on alternate strokes is not obtained due, for one reason, to the subtraction of the cross-sectional area of piston rod from the area of the piston face on the side opposite the piston rod. Accordingly, the mechanism operates with greater force in one 20 direction than it does in the opposite direction. A primary object of my invention is to provide a clipper mechanism which has actuating means supplying pressure to the knife proportional to the requirements of the cutting operation.

25 30 A primary object of my invention is to provide a veneer clipper comprising a knife means and an expandable-collapsible pneumatic actuating means for said knife means.

An object of my invention also is to provide 35 a veneer clipper which is capable of high-speed operation, and which makes it possible to speed up production in a plywood manufacturing plant, and this with marked economy both in raw material and in operating expense of mechanism.

40 Another object of my invention is to improve the construction of veneer clippers of this type and to render the same more reliable and efficient in operation.

45 A primary object is to provide a veneer clipper having a knife carrying assembly mounted for oscillating movement and having at least one expandable-collapsible pneumatic member positioned to exert a pressure against a part of said knife carrying assembly to move the same and stroke a knife carried thereby.

50 A serious objection obtains to veneer clipper mechanism as commonly employed in that a brass anvil is provided against which the knife does strike. This, in part, accounts for the seriously excessive and violent mechanism disrupting vi-

bration. A primary object of my invention is to provide a clipper mechanism having an anvil which provides the common functions of an anvil in the commencement of the clipping operation without the possibility of the knife striking the anvil in direct contact—such striking being avoided by having the knife rotate in its downward stroke so as to provide a veering off or clearance action as the knife edge approaches the anvil, revolves to a point sufficiently in front of the anvil edge to miss the same, and providing a shearing action as the end of the stroke is approached. This mode of clipping or severing also provides a clipped edge of the veneer which presents a greater area, being on a curve, for the purpose of edge gluing than it would if the clipper cut the sheet at right angles to the plane of the veneer.

Another object is to provide a clipper having resilient hold-down members carried by an oscillating knife carrying assembly and adapted to engage with and stop the veneer just before the veneer is contacted by the knife on its cutting stroke.

Another serious problem presented by the sheet of veneer of the character herein involved coming from the peeled log is as follows: The knots and decayed portions or pitch portions, and the different stresses existing in the weight of the veneer causes the sheet to be warped so far as lying flat upon the table over which the conveyor belts run in moving the veneer to the clipper mechanism. It is highly important that the veneer sheet move at a uniform rate and when stopped, even momentarily, by the knife action in clipping through the sheet, that it be caused to resume its advance over the table promptly and with the edge square to the table. In accomplishing this, a serious problem arises due to the fact that the sheet does not lie uniformly upon the table with its carrier belts, and since its advance over the table is dependent upon friction of the veneer sheet against the carrier belts, often it does not receive equal forward thrust from the carrier belts. However, the fact of the presence of the knot holes and decayed sections and pitch pockets, and above all, the thinness of the veneer sheets, allows the sheet to buckle and not be moved forward squarely and with uniform advance until a considerable period after the sheet is caused to resume its movement after momentarily being stopped. A primary object of my invention is to overcome this difficulty and to not only cause the veneer sheet to stop its advance just prior to the knife action, but also to hold the sheet in fixed position while the knife rises and thereby is wiped clean of any pitchy material, and to employ the same holding mechanism that operates to stop the sheet, to cause the sheet to resume its advance. In other words, the stopping mechanism is employed to give an initial start or thrust to the leading edge portion of the veneer and thereby not only give it the start in resuming its advance, but also to cause the edge to move squarely forward. Furthermore, this stopping mechanism is employed to use its curved shape to help overcome any curling tendency of the leading edge portion, and thereby provide for the leading edge to pass promptly beneath the upraised knife edge.

A further object of my invention is to provide for a positive veneer sheet feed mechanism to the knife, one which is spring loaded, to provide down pressure and is moved positively upward from the veneer sheet at the time of clipping

5 to stop its feeding action. Yet, due to the location of the spring loading and the method of providing positive upward lifting action, varying thickness of the veneer sheet can be accommodated by this feeding mechanism while the feeding action is in progress. The feeding chain of this feeding mechanism is inclined towards the veneer sheet. This inclination facilitates the gripping of the curled leading edge, and at the same time, such inclination enables providing for quick clearance from the veneer sheet when the feed means is to temporarily cease feeding the material.

10 Another object is to provide means by which the veneer is fed to the clipper knife by providing a rotary device of a paddle wheel type which has flexible arms and which operates in conjunction with a chain feed mechanism of my invention to engage with and tuck an upcurling leading edge portion of the veneer beneath the chain feed in a single thickness thereby providing for causing the sheet of veneer to advance beneath the knife without any destructive force being applied thereto—the ends of the paddle 15 co-acting with the sloping portion of a chain feed, and having its peripheral path intercept the chain feed at a critical point in spaced relation to the table top, so that the veneer sheet is not jammed by the paddle against the top of the feed table, and some degree of freedom for the sheet to avoid 20 crushing. Thus, the sheet of veneer is left in such angular repose that the chain feed is allowed to continue the flattening action of the curled leading edge without injury thereto and gradually cause the curled edge to assume a 25 parallel plane with the infeed belts.

25 Furthermore, as respects a backcurl on the following edge of a sheet (it being remembered that the veneer sheet is not always of ribbon form, but the peeler knife may be intermittent in its action due to the shape of the log), the combination of the paddle wheel and feeding mechanism of my invention cooperate in a particularly advantageous manner in uncurling the sheet. The sprocket operating the chain feed mechanism of my invention operates in synchronization with the belt feed, and at the same rate of lineal feet per minute as the feed belt. The paddle wheel which is mounted on the same shaft as the drive sprocket of the feed chain will provide different speeds depending upon what part of the arms is in contact with the product, the ends of the paddle arms moving faster than the inner portions. This increased peripheral speed 30 of the ends of the paddle while operating advantageously on the front curl due to interrupting arcs being formed by the curl of the sheet and the arc at the end of the arm, would operate disadvantageously on the backcurl because the arc of the arm and the curl of the sheet are 35 near similar in their center, and as the sheet is progressing steadily forward at the rate of the feed belt, and is continuously decreasing the trailing edges positioned relative to the radius of the arm, it reaches a point when contacting the chain whereby these speeds are equal—the speed of the feed belts varying in different plants from 40 90 to 140 due to the ability of the clipperman to handle inferior material.

45 A primary object of my invention is to provide clipper mechanism peculiarly adapted and subject to being controlled by electronic means. The construction of the clipper of my invention, particularly its actuating means, is capable of such instantaneous and responsive action that it

works exceedingly well in conjunction with the speed of electronic means. Such inherent speed of operation of the actuating means of the clipper mechanism of my invention operates to make the clipping action directed to the definite narrow limits forming the border of the defective parts, and to the dimensions of predetermined panel sizes. Thus, only the defective part may be removed and not adjacent good material by reason of the lag in the operation of the clipper knife actuating means, and also the desired precise dimensioned panel provided.

These results are provided by my invention by providing a definite arc of travel of the knife. In pneumatic means employing cylinders and pistons there is the inherent necessity of an air cushion at the end of the stroke of the piston which exhausts slower than the previous exhaust. Thereby, during repeated actuation, the length of stroke of the piston is varied with the amount of cushion which has been bled prior to actuation. In the pneumatic actuating means of my invention no such bleeding exists. At the end of each stroke a positive predetermined position is reached and the knife starts uniformly and necessarily from this predetermined point. The travel time of the knife edge from this predetermined point (that is, in its most up-raised position) must be in direct sequence with the forward travel of the sheet which is continuously running until interrupted by pressure feet or momentarily stopping mechanism and knife. If inaccuracy is to be avoided, my invention provides for the elimination of all such inaccuracy.

In developing the invention, I discovered that there was a back pressure developed upon the exhausting of the pneumatic means of such large proportions that the knife mounting mechanism was caused to deflect. An object of my invention is to provide means for overcoming deflection of the knife edge. In connection with overcoming such back pressure, and in providing for change of direction of the knife rocker assembly, it was found that the location of the bumper means was very important, and an object of my invention is to provide for locating the bumper mechanism to absorb shock in a position which will prevent deflection of the knife edge, as is hereinafter set forth.

Other objects will be apparent from the following description taken in connection with the accompanying drawings.

The above-mentioned general objects of my invention, together with others inherent in the same, are obtained by the mechanism illustrated in the following drawings, the same being preferred exemplary forms of embodiment of my invention, throughout which drawings like reference numerals indicate like parts:

Figure 1 is a top plan view of a veneer clipper embodying my invention;

Fig. 2 is a view in rear elevation of the same, looking in the direction of the broken line 2—2 of Fig. 1, parts being broken away;

Fig. 3 is a view in vertical cross-section with parts in elevation, taken substantially on broken line 3—3 of Fig. 1;

of spring means for air cell means on one side of the rocker means;

Fig. 7 is a diagrammatic view showing pneumatic means, air control valves and electronic control means therefor; and

Fig. 8 is a view in plan of the control panel.

The frame of this clipper comprises two upright end frame members 10 and 11 of similar construction. The end frame members 10 and 11 are supported in spaced apart relation by a fixed backing frame or upper cross member designated generally by 12 and a lower cross frame member designated generally by 13. Preferably the fixed backing member 12 is made up of an air reservoir portion 30 and two convergent backing plates 22 and 22', all rigidly secured together. The end frame members are herein illustrated as being built up of metal plates welded together to provide box-like structures having great strength and rigidity. Each end frame member 10 and 11 has a base portion 14 of substantial area, and further, has a relatively flat vertical inner face portion 15 to which the cross members can be secured. The structure just described provides end members of hollow construction with space inside for housing bearings and other parts as hereinafter described.

The fixed backing frame member 12 as herein shown in Figs. 3 and 4, is provided with rigid end flanges 16. These end flanges 16 are adjustably secured to the face portions 15 of the adjacent end frame members 10 and 11 as by bolts 17 and adjusting screws 18. The bolts 17 preferably pass through vertical slots 19 in the end flanges 16 and are anchored in the adjacent end frames. The adjusting screws 18 functioning as a jack for the fixed backing frame are threaded downwardly through boss portions 20, which are rigid with the fixed backing frame 12 adjacent each end thereof. The lower end portions of these adjusting screws 18 (see Fig. 4) rest on lugs 21. Preferably, two adjusting screws 18 are provided at each end of the fixed backing frame member 12 thereby providing for vertical and angular adjustment. When the nuts on bolts 17 are loosened, then turning of the adjusting screws 18 will adjust the fixed frame member 12 vertically relative to the adjacent end frame. When the nuts on 17 are tightened, they will rigidly secure the cross frame 12 to the end frame members.

The lower cross frame 13 preferably comprises two plates 23 which are spaced a short distance apart at their upper edges and diverge toward their lowermost edges. The end portions of the plates 23 are rigidly secured to end flanges 24. Each end flange 24 has vertical slots 25 for the reception of bolts 26 by which the end flanges 24 are adjustably secured to the end members 10 and 11. Each plate 23 has spaced apart upright stiffening flanges or webs 27 welded or otherwise rigidly secured thereto to reinforce and stiffen and lend strength to the lower cross frame. Also, each plate 23 has an inwardly directed narrow horizontal flange 28 welded to the lowermost edge thereof. The flanges 28 act as reinforcing and stiffening members and also function as sound deadening members to offset and neutralize the tendency of the divergent frame members 23 to amplify noise.

One of the great objections to veneer clipper mechanism as commonly constructed and employed heretofore, is the great amount of noise that is developed by reason of the operation of the same. One of the objects of the present in-

vention is to overcome and reduce to a minimum such objection of noise and vibration.

Preferably, two adjusting screws or jacks 29 are provided for adjusting each end portion of the lower cross frame 13. As herein shown in the drawings, as preferably construction, each jack screw 29 has a head 30 which is supported in a channel shaped member 31. Each channel shaped member 31 rests on and is supported by one of the end frame base members 14. Each screw 30 extends upwardly through a horizontal plate 32 which is rigid with the lower frame parts 23, 24 and 27. Two nuts 33 are threaded onto each screw 29 on opposite sides of the plate 32 and can be used to vertically and angularly adjust the lower frame 13.

An anvil bed-bloc 34, (Figs. 3 and 4) extends across the clipper and is supported by the lower frame 13. This anvil bed-block 34 has a downwardly extending flange positioned between the plates 23 and preferably is provided with two shoulders 35 which rest on the top edge portions of the plates 23. The upper edge of this anvil bed-block 34 is provided with a longitudinally extending substantially U-shaped groove 36 for the reception of a readily removable and interchangeable anvil or shear member 37. The anvil or shear member 37 has one beveled corner 38 which cooperates with the top of said anvil in providing a shearing edge 39. Bolts 40 can be used to secured the anvil 37 to the anvil bed-block 34. This form of the anvil 37 and its position with respect to the knife 51, which is hereinafter described, provides for the anvil to give direct support to the veneer during the movement of the knife through a portion of its arc of stroke, and at the same time provides for the knife at the bottom portion of its stroke to revolve inwardly of the edge of the anvil so that at no time could the knife strike the anvil.

For feeding veneer over the anvil or shear member 37, the feed means shown in Figs. 3 and 4 comprises feed belts 41 for feeding veneer 42 to the clipper and off-bearing belts 43 for carrying away the clipped veneer. Plate means 44 can be provided for supporting the veneer immediately adjacent the anvil 37. The belts 41 and 43 can be carried on suitable rollers 45 and 45' and can run on track members 46. Rollers 45 and 45' are preferably of relatively small diameter in order to cooperate with adjacent structure to permit belts 41 and 43 to run as close to the anvil 37 as possible.

The veneer clipping means, as shown in the drawings, includes a rocker means, identified in general as 9, formed of a tube 47, two divergent plates 48 and 49 arranged in shape of a V, and a tool or knife carrying plate 50. A knife 51 is secured to the knife carrying plate 50 as by cap screws 52 which extend through slots 53 in the knife 51 and are threaded into the plate 50. Preferably reinforcing web means 54 is provided between the knife carrying plate 50 and the tube 47 and plate 49. Also, preferably web means 55 is provided on the outer side of the plate member 48. Preferably a shaft 56 extends throughout the length of the tube 47 and said tube 47 is journaled on the shaft 56, as by bearing means shown in detail in Fig. 5 and more fully hereinafter explained. The rocker means 9 is adapted to be oscillated about the axis of the shaft 56 to impart cutting and retractile strokes to the knife 51. The weight of the plate 50 and knife 51 provide an eccentric load to the rocker means

9 which in turn provides for an impact blow as the cutting or shearing force.

The fixed backing frame 12 is positioned with the air reservoir cylinder 80 uppermost and with its two convergent backing plates 22 extending downwardly in convergent relation toward the tube 47, thereby providing an exceptionally strong backing frame. The divergent plate members 48 and 49 of the rocker means 9 extend divergently upward and outward alongside of and in spaced relation from the downwardly extending convergent backing plates 22 and 22' of the fixed backing frame 12 so that the rocker means 9 is free to rock or oscillate relative to the fixed backing frame 12.

The rotational axis of the rocker means 9 and the longitudinal axis of the fixed backing frame 12 are thus parallel and in spaced relation to each other. The substantial V-shape form of the plates 48 and 49 oscillating in relation to the convergent plates 22 and 22' of the fixed backing member 12 provides an important feature of my invention, namely, a variable shaped space between the plates 48 and 49 and plates 22 and 22' alternately during the stroke operation. This variable shape of space results in a jaw-like action upon the expandable-collapsible air cells 57 and 57' and 58 and 58' (shown by dotted lines in Fig. 2 and shown in Figs. 4 and 7). The rotational force is thus increased due to the eccentric loading and thereby providing a rotation force required by the load. The thicker the sheet of veneer 42 being cut, the higher will the point of the knife edge be above the table, and therefore the air cell will be at the time of engagement of the product with a large bearing area on the plate 49. As the air cell 58 enlarges by reason of the admission of air under pressure, the less area does it bear upon the plate 49. Remembering that in splitting or cutting wood, it is the initial impact that is the important matter. After the impact of the knife against the fiber and the splitting or dividing of the fibers is under way, then the force required is lessened. Also, remembering that the air pressure is constant, my invention provides for a relatively great area to start initially the rotation of the rocker means 9. This relatively large area of air cell bearing initially provides for a great force in starting the rotational force imparted to the knife and the eccentric loading continues to build up to an impact that operates most advantageously in severing wood fibers upon contact of the knife edge therewith.

Another important feature of my invention is that in starting the rotation of the rocker means 9 on the cutting stroke, the air cell 58 is in largely or partially collapsed condition, and therefore requires the admission of little air to fill the same. As the air cell is under constant pressure and the bearing area relatively large, the force developed is relatively great, and since the amount of air is small it requires but a very short period of time for transfer of air to perform the above function of initially applying great force to the rocker means 9 in starting the rotational action.

The providing of a variable shaped space between the plates 48 and 49 on the one hand, and the divergent plates 22 and 22' of the fixed backing member on the other hand, provides for the air cell members, as 57, to take a pear-shape form during a portion of the bearing area stroke thereby maintaining relative equality between the members. In other words, the flexible expandable-collapsible character of the air cell charac-

terizing my invention makes it possible for the air cell to adapt itself to the varying shaped space, thereby rendering it possible to use one movable member, as the rocker means, in conjunction with a fixed backing frame in a very simple arrangement.

A distinctive feature of my invention is that such great forces are developed in this simple manner that it requires an exceedingly strong fixed backing frame in order to absorb the reaction forces. There is a tremendous deflecting force created and particularly is this true when the backing frame 12 is relatively long between fixed supports whereby considerable movement is developed at the center. The providing of a reservoir 80 between the convergent plates 22 provides for a particularly simple, strong structure, and provides for reducing the time transfer of the air reservoir to the respective air cells with a minimum loss of pressure due to volume change. High-speed action is required and this is one of the features which characterizes my invention. Moreover, it will be noted that the one fixed backing structure provides for both directions of movement of the rocker means 9.

The means herein shown for imparting oscillation or rocking movement to the knife carrying rocker means comprises four collapsible tubular air tight hose members 51, 57', 58 and 58'. The plurality of hoses has been found important in increasing the speed of oscillatory action of the rocker means 9, and also, which is of particular importance, it was found that the deflection forces were greatly thereby reduced. This is true because the moment arm of force is less than the moment arm of reaction—the rotational force of the air cells in the structure shown herein is applied to the rocker means relatively near the bearing points and no force is applied at the center. This results in the corresponding reaction force being applied relatively near the fixed mounting of the fixed backing frame rather than at its relatively unsupported central portion. Air cell members 51 and 57' on one side, are positioned between the plate 48 of the rocker means 9 and the backing plate 22 of the fixed backing frame 12, and air cell members 58 and 58' on the other side, are positioned between the plate 49 of the rocker means 9 and the backing plate 22' of the fixed backing frame 12. The air cells 51, 57', 58 and 58' may be heavy duty fire hose, or specially constructed expandable-collapsible air cell means providing they are airtight pneumatic members, capable of withstanding pressures required for the particular operation involved, and of a character which does not permit them to substantially change their peripheral dimensions.

When the hose members 51 and 57' are free to collapse and the hose members 58 and 58' are inflated, as shown in Fig. 3, the rocker assembly will be angularly moved clockwise and a cutting stroke will be imparted to the knife 51. Conversely, when the hose members 58 and 58' are free to collapse and the hose members 51 and 57' are inflated, as shown in Fig. 4, the rocker assembly will be angularly moved counter-clockwise and the knife 51 will be retracted. This pneumatic actuating mechanism is smooth, efficient and powerful in operation and is capable of high-speed operation with minimum wear. By referring to Figs. 3 and 4, it is manifest that at the time of cutting, the force is relatively vertically applied to the product above the anvil 37, thereby causing the product 42 to take the major

force of the thrust without applying an equal reaction force to the bearing. In this construction, the momentum of moving parts incident to the stroking and retraction of the knife is reduced to a minimum and the shock is cushioned in such a manner as to minimize vibration.

Plate 48 carries bumper means 59, which is designed to function primarily as a protective bumper means to prevent injury to the air cells 57 and 57', and said bumper means 59 ordinarily may not strike against plate 22. Said bumper means 59 preferably extends longitudinally of plate 48 throughout at least the length of their respective air cells 57 and 57', and can extend throughout the entire length of the plate 48.

Plate 49 carries bumper means 60. This bumper means 60 extends throughout the length of the plate or throughout the length of the respective air cells 58 and 58'. Said bumper means 60 actually strikes against plate 22' absorbing full impact of the rocker means 9 on the retractive stroke.

A third bumper mechanism referred to in general by the numeral 100 is located on each end of the fixed backing frame 12 and may comprise a pair of rods 101 in spaced relation longitudinally of the fixed backing frame 12 and said pair of rods is fixedly secured to the fixed backing frame 12. Each of these rods passes through a slot 102 in an extension 103 secured to the upper edge of plate 49. These rods 101 in the particular structure shown are about one foot apart. The backing plate 104 is slidably mounted on rods 101 extending across to the other member of the pair, and is held by adjusting nuts 105. A rubber bumper 106 preferably molded in a dove-tailed channel member 107 is slidably mounted on rods 101 but adjustably held by nuts 108. The mode of operation of this third bumper is as follows:

In the first place, it measures the depth of stroke of the knife. In the second place, it functions at the time of change of direction of oscillation of the rocker means 9 to impart a rebound action to the plate 49 thereby overcoming any tendency for lag of air in transferring to the air cells. As a matter of sequence of action, air is exhausted in air cell 58 and the rocker is in coasting action in engaging the rubber bumper 106. The bumping thus gives a rebound action initially starting the rocker 9 in the opposite direction, that is, retractive stroke, and immediately the air pressure in the air cell 57 catches up with the retracting plate 49 and moves the rocker means speedily in a counter-clockwise direction. In this way the air lag is overcome and high-speed action is provided.

Resilient curved product braking means 61 are adjustably secured to the tube 47 and disposed in spaced relation to each other as follows: A capping plate 65 extending substantially throughout the length of the tube 47 is fixedly secured to tube 47. This capping plate 65 may have stud bolts 63 mounted therein disposed adjacently and on each side of the braking means 61. Over the braking means 61 and slidably mounted is clamping plate 62 slidably mounted on bolts 63 and held firmly against braking means 61 by nuts 64. Braking means 61 is preferably of leaf construction with the lower end portion slightly upwardly curved to avoid marring the product. Braking means 61 is adjusted to stop short of the arc path 66 of the point of the knife 51, so that the end of braking means 61 at no time intersects the arc 66 and thus the braking means 61 engages the product 42 prior to the time that the knife 51 con-

tacts the product and thus temporarily stops the advance of the product—the knife cutting with the product stationary. The braking means 61 stops the product prior to engagement of the knife with the product because of its attachment to the tube 47. Its adjustment with respect to the rotation of the knife is such that the datum of the lower portion of the braking means 61 is always lower than the point of the knife 51 until the braking means 61 engages the product surface and stops the advance of the veneer product 42 and permits the knife thereafter to descend through the veneer product 42.

The further oscillating of the rocker means 9 causes further compression of the braking means 61 against the surface of the veneer product 42, shortening the distance from the axis of the rocker means 9 to the end of the braking means 61. As the knife initiates its retracting stroke and is moving in a forward direction, that very moment the braking means 61 begins moving forward and gives initial thrust to the veneer product 42. Since the knife is withdrawing in a backward direction at a faster rate than the incoming feed and the material is being held against the feed belts, it is not allowed to follow upwardly with the knife. The immediate thrust of the braking means 61 due to the reverse direction of the oscillating of the rocker means 9 immediately starts the veneer product 42 beneath the knife as the knife starts upward, but as the knife is moving upwardly faster than the advance of the veneer product 42, there is no interference.

A further function of the braking means 61 is as follows: Any tendency of the front edge of the advancing veneer product 42 to curl upwardly is prevented by the curved form of the braking means 61 and the fact that the lower edge portion of the braking means 61 is always at a lower datum than the point of the knife 51. Thus the braking means 61 performs four functions (a) deflector of the veneer against curling, (b) acts as a brake momentarily stopping the advance of the veneer product, (c) acts as a hold-down for the veneer by reason of the compression strains in the braking means 61 to permit the knife to clear the veneer product in its retracting stroke, and (d) acts to impart an initial thrust to the leading edge of the veneer product.

A real problem has been presented in veneer clipper mechanism in providing feeding means to start the veneer product on its advance after being momentarily stopped by the knife while performing the clipping operation. Heretofore the common practice has been to provide the continuously running roller chain contacting the upper surface of the veneer and its loading being a balanced gravity load of a degree of contact friction to allow the roller chain to slip over the surface of the veneer during the momentary stopping of the veneer during clipping, yet of such load capacity to actuate the forward travel of the veneer by the friction of the roller belt thereby having contradictory functions of load on the roller chain—on the one hand, such degree of lightness as not to mar the surface of the veneer and permit slippage, and on the other hand, of such degree of force as to feed the material forward after the obstruction of the knife was removed.

Accordingly, on shaft 67 is pivotally mounted a pair of roller feed chain brackets 68. These brackets 68, in the present machine, are spaced

about two and one-half inches and are rigidly held in such spaced relation by means of a spacer member 69 to which a hardened faced shoe member 70 is secured. Also, stub shafts 71 and 72 operate to hold the bracket members 68 in spaced relation. On these shafts 71 and 72 are mounted idler sprockets 73 and 74. Driver sprocket 75 is mounted between the brackets 68 and fixed to the shaft 67 to be driven thereby—the pitch circumferential speed is synchronized with the speed of the driving belts 41 being driven in a counter-clockwise direction. A feed chain 76 is mounted on driver sprocket 75 and idler sprockets 73 and 74. A chain tension sprocket 77 is mounted on shaft 78 rigidly fixed to bracket 79 and hinged on stub shaft 71. This tension sprocket 77 is adjustably positioned by bolt 81. The tension of the chain 76 is very important as it must extend beneath shoe 70 in close contact therewith and must extend in an inclined position back to sprocket 73 in a straight line without any substantial sagging so that when as hereinafter described the feed chain bracket is raised there will be no contacting of the veneer product 42. A compression cross member 82 mounted on top of the brackets 68 and preferably located about half-way between shaft 71 and shaft 72 provides a mounting means for stud bolt 83 midway between the members forming the feed chain bracket 68. On capping plate 65 is rigidly mounted bracket 84 of channel shaped cross section. In the end is a slot 85 receiving stud bolt 83. A rubber washer 86 on stud bolt 83 is held in place by lock nuts 87. A compression spring 88 is mounted around stud bolt 83 in a recess 89 in compression cross member 82 and extends upwardly against bracket 84. When the rocker means 9 oscillates clock-wise carrying the knife 51 downwardly for clipping operation, and therefore momentarily blocking the advance of the veneer product 42, the feeding of the product must likewise stop. To accomplish this, bracket 84 being mounted on tube 47 opposite to the knife 51, is moving upwardly and thereby lifts the brackets 68 and feed chain 76 clear of the veneer product 42, causing the said bracket to rotate on shaft 67 to a height equal to the distance of the knife substantially above the level of the table when in raised position. Thus, all feeding action of feed chain 76 of the veneer product 42 is stopped and there is no tendency to cause the veneer product 42 to jam against the knife 51 during the time that the knife 51 is momentarily blocking the advance of the veneer sheet 42 during clipping operation. Moreover, if the feeding action of the feed chain 76 was not thus interrupted, it would overcome the braking operation of the resilient braking means 61.

As the knife 51 raises on its retracting stroke, obviously bracket 84 is revolved counter-clockwise and thereby moves against compression spring 88 and forces downwardly feed chain 76 against the veneer product 42 with a predetermined load causing a squeezing of the veneer product 42 between the moving feed belt 41 and the moving chain 76, causing a positive feed forward immediately following the initial thrust given to the veneer product 42 by the braking means 61 as hereinabove described.

It is to be remembered that the veneer product 42 is not always of uniform thickness. Pieces of knot may break out and lie on top of the veneer product, or sometimes portions of the veneer sheet product 42 overlap so as to provide varying thicknesses. Also, when the peeling log is initial-

ly rotary cut, the shape of the log may be such as to provide varying thicknesses for the veneer sheet product 42 thereby requiring a feed means capable of accommodating such non-uniform thickness of veneer product 42. The compression spring 88 adapts the feed mechanism of my invention for adjusting itself to such non-uniformity of thickness of veneer product. The shoe member 70 in operating position extends substantially parallel to the feed belt 41 thereby ensuring a substantial extent of contacting area for the chain 76 with the veneer product 42 to ensure proper feeding action. The parts numbered 68 to 89 inclusive form a feed mechanism assembly of which there are a plurality, disposed in spaced relation transversely of the machine and are disposed immediately above corresponding feed belts 41. The angle 90 of the chain 76 between the tip of the shoe 70 and the sprocket 73 in relation to the veneer product 42 is important in that it must be such as to provide a quick clearance for the advancing veneer sheet 42 when being raised, and when in lower position to be capable of providing an ease of angle of receiving the advancing edge to uncurl any slight curled portion of any such advancing edge.

Adjacent to each of the brackets formed by the pair of members 68 is a hub 91 which is rigidly secured to shaft 67 to be driven thereby in a counter-clockwise direction. Lugs 92 are positioned parallel to quad radii of the hub 91. To these lugs 92 are secured two semi-flexible radial arms 93 forming a paddle-like construction. These arms 93 function to engage any curled advancing edge of the veneer product 42 and operate to uncurl such curled edge and feed the same beneath feed chain 76. The length of these arms 93 is such as to extend to a horizontal plane intersecting the point where the chain 76 leaves the sprocket 73, thereby uncurling any curled portion of the advancing edge of a veneer sheet to such a position as to be readily received by the chain 76 as it enters between the chain and the feed belts forming the angle 90. Of course, it will be understood that the ends of arms 93 do not contact the veneer product 42 unless the same is in curled position. Since the peripheral speed of the ends of the arms 93 exceeds the lineal speed of the veneer product 42, a curled up-turned edge portion is advanced faster than the main body of the product 42 and therefore is uncurled and the leading edge deposited within angle 90.

In addition to feed and hold down means 76 and 93 I preferably provide a plurality of spaced apart curved metal hold down members 93A. Members 93A are floatingly supported by shaft 67 and extend toward the knife 51 and rest on the product 46 and cooperate in straightening out and holding down the product.

Relative Fig. 5 and bearing construction for tube 47 and shaft 56: The bearing comprises a conical roller bearing 56A on the shaft 56 supporting the tubular member 47 for oscillation. The shaft 56 extends beyond the end of the tubular member 47 and is supported in a sleeve 47A which is threaded into a hub member 47B. The hub member 47B is fixedly secured as by bolts 47C and taper pins 47D to web members 47E which are rigid with the end frame 10. Preferably, the end portion of the shaft 56 is threaded and nut and washer means 47F on this threaded end portion engage with the sleeve 47A and prevent longitudinal movement of the shaft 56 to the right as respects the showing in

Fig. 5, and acts as a locking means after sleeve 47A has been adjusted to bearing 56A. This arrangement prevents longitudinal movement of rocker means 9. To facilitate the retention of lubricating material around the bearing 56A in chamber 56B, I preferably provide packing ring means 56C between the hub 47B and the tubular member 47, and further provide on the shaft 56 a grease retaining ring 56D which is held by collar means 56E and contacts the inner wall of the tubular member 47. Thus long-time lubrication is provided.

In Fig. 6 a modified form is shown where a compression spring means is substituted as an actuating means for actuating rocker means 9 in place of one air cell, as 57. Compression springs 101A are mounted on rods 101 between extension 103 and backing strip 104. The resilient bumper 101B in the modified form is of a height that will be greater than the compressed height of spring 101A so that it may perform its resilient bumper function.

Compressed air from a suitable source is supplied through water trap 94 to pressure regulating valve 95 and thence to air reservoir 80. A standard 4-way solenoid controlled pneumatic pilot operated high-speed valve 96, commonly supplied on the market, is mounted immediately above and between air cells 57 and 58, and likewise, a similar 4-way valve 96A is mounted between air cells 57' and 58'. The intake port of the 4-way valve 96 is connected by conduit 97 to reservoir 80 to receive compressed air. One of the distribution ports of said valve 96 is connected by conduit 98 to air cell 58 through tube 98' in reservoir 80. Another distribution port of valve 96 is connected by conduit 99 to air cell 57 through a tube 99' in reservoir 80 (see Fig. 2).

Similarly, the intake port of 4-way valve 96A is connected by conduit 97A to reservoir 80 to receive compressed air. One of the distribution ports of said valve 96A is connected by conduit 98A to air cell 58' through tube 98B in reservoir 80. Another distribution port of valve 96A is connected by conduit 99A to air cell 57' through a tube 99B in reservoir 80.

The exhaust port of the 4-way valves 96 and 96A exhausts to the atmosphere. Supplementary exhaust solenoid operated exhaust one-way valves 109 and 110 are respectively connected to conduits 98 and 99. By supplying these supplemental exhaust means, development of back pressure in the exhausting air cells is reduced to a point where such back pressure is unobjectionable, and thus provides for speeding up action of rocker means 9. Likewise, supplementary exhaust solenoid operated exhaust one-way valves 109A and 110A are respectively connected to conduits 98A and 99A.

Switch arm 111 is fixedly mounted on the end portion of tube 47 (see Figs. 2 and 5) and engages a standard 2-circuit 4-pole delayed action limit switch lever arm 112. Divergent plate 49 is provided with a resilient switch actuating arm 113 adapted to engage contact member of normally closed switch 114.

The above mechanical construction as has been indicated is designed for high-speed operation, and is therefore specially adapted to be operated by electronic control means. Such a means will next be described.

On a frame means 115 which are adjustably clamped are lights 143, 143a, 143b, 143c and 143d, the same preferably comprising electric

bulbs with concentrating lens of standard construction to provide a light beam. These light beams are directed to reflector means 117, 118, 119, 120 and 121 which direct the light to a photo-electric relay unit 150. The above described sources of light and their corresponding reflectors are in such spaced relation as to provide a controlled distance from the clipper knife 51 so that pre-determined sizes of veneer panels may be cut. The light beams pass through the path of travel of the veneer product 42 on the off-bear belt, and therefore, said light beams are interrupted by the leading edge of the veneer product to be clipped, and therefore, the leading edge of the product itself is used as the self-measuring device.

By way of illustrating the operation of one automatic control mechanism as set forth in wiring diagram Fig. 7, the mode of operation will be described as applied to the cutting of a panel width of 24", it being understood that the other widths, such as 12" being controlled by light 143d, that is, the light nearest to the knife 51, and the width 24" being controlled by light 143c, and the width 30" being controlled by light 143b, and the width 36" being controlled by light 143a, and the width 48" being controlled by light 143. The description, which will now be set forth for the control means, is that set forth in part in my application Serial Number 778,705 filed October 8, 1947, for "Automatic Electronic Control Mechanism." To resume, the mode of automatic operation for cutting a 24" width would be as follows:

Depress push button 210b. This button closes the circuit to the relay 229(2.R) between secondary line 206(L.3) and main supply line 196(L.2). Relay 229(2.R) has two contacts normally open 230(2.R.1) and 231(2.R.2) and normally closed contact 232(2.R.3). When relay 229(2.R) was energized by depressing button 210b contact 231(2.R.2) is closed, which is the counter circuit, but is unenergized until contact 191(S.R.1) and contact 195(S.R.2) are closed at the time of clipping by the knife 51. When contact 230(2.R.1) is closed it becomes a holding contact and replaces the depressed button 210b and contact 232(2.R.3) in line 206(L.3) is opened thereby de-energizing all lights beyond 143c(2.L). Thus lights 143d(1.L) and 143c(2.L) have their beams concentrated and reflected upon photoelectric cell 150 thereby energizing the cell relay 220(P.E.) and causing the closing of contact 222(P.E.2), thereby energizing relay 205(A.R.) allowing current to flow from main supply line 192(L.1) across to supply line 196(L.2), and thus closing contact 204 (A.R.1) which acts as a holding contact for relay 205(A.R.) and contact 223(A.R.2) is in series with relay 225(S.R.), but is inoperative until relay 220(P.E.) of the photoelectric cell unit 150 is de-energized by the advancing sheet of veneer 42, Fig. 1, which cuts off the light beam.

All this occurs as follows, referring further to the wiring diagram Fig. 7:

As the flow of the veneer sheet 42 interrupts lights 143d(1.L) and 143c(2.L) progressively (that is, they both have to be covered), the photo-electric cell 150 becomes darkened and de-energized which causes the photo-electric cell relay 220(P.E.) to close contact 221(P.E.1)—normally open contact 223(A.R.2) having been previously closed by the light energizing photoelectric cell 150 as above explained—which now allows current to flow from main line 192(L.1)

through contact 221(P.E.1), that is, closed 221(P.E.1), through closed contact 223(A.R.2) thereby energizing relay 225(S.R.) which is connected with main line 196(L.2). Relay 225(S.R.) closes contacts 191(S.R.1) and 195(S.R.2).

At this point there are some changes in mode of operation and type of contacts from that set forth in said previous application. Instead of having mechanically operated limit switches 198(L.S.1) and 199(L.S.2) mechanically actuated, in the present invention these normally closed contacts are now opened by the energizing of the relay coil C.R.122, which has two normally closed contacts 198(C.R.1) and 199(C.R.2). Assuming that rocker means 9 is in raised knife position, the switch actuating arm 111 has mechanically operated limit switch 112 by moving contactor bar between contacts 123 and 124, and has closed the circuit between contacts 123 and 124 and opened the circuit between contacts 125 and 126. As contact 191(S.R.1) and contact 195(S.R.2) were previously closed, as described, a circuit is now completed from 192(L.1) through closed contact 191(S.R.1) through contacts 123 and 124 to solenoid in valves 96 and 96A on one side 121 of a 2-wire circuit. The other side of circuit starting from line 196(L.2) passing through previously closed contact 195(S.R.2) completes the energizing of the solenoid in valve 96A and the solenoid in valve 96. These valves having been energized and compressed air admitted to conduits 98 and 98A which is fed to air cells 58 and 58', expansion of these air cells rotates rocker means 9 through their contact force to cause cutting action. As air cells 57 and 57' are exhausting through valves 96 and 96A, additional supplementary exhausting one-way solenoid valves 110 and 110A are provided and are operated for further exhausting in the following manner: An additional parallel circuit 132 and 133 which joins circuit 127 and 128 in parallel and energizes a solenoid 4-contactor relay 129-(D.R.) having contacts D.R.1, D.R.2, D.R.3, and D.R.4, closing contacts D.R.1 and D.R.2, completing a circuit from line 135 through contact D.R.1 through normally closed switch 114, and continuing as one side to the solenoids 110 and 110A. The other source of energy to these coils 110 and 110A is derived from the other side of the circuit line 134 through contact D.R.2 to solenoid 110A by contactor 130, completing the energizing of coils 110 and 110A, exhausting air at these points from air cells 57 and 57'. As rocker means 9 takes limit of cutting position, normally closed switch 114 is contacted by flexible arm 113 mounted on plate 49 of rocker means 9 and opens this normally closed switch which deenergizes by breaking circuit 131 and valve coils 110 and 110A in order to avoid escaping air when air cells 57 and 57' are re-inflated. The reversing action as later described re-closes switch 114 as lever arm 113 leaves contact with switch 114. Rocker means 9 now takes limit of cutting position reversing limit switch 112, opening the circuit between contacts 123 and 124 and closing the circuit between contacts 125 and 126 by connector bar of relay 112. The opening of the circuit on line 127 and 128 now de-energizes coils in valves 96 and 96A and reverses the flow of air from exhaust air cells 58 and 58' and inflating air cells 57 and 57'. D.R. relay being in parallel with lines of circuit 127 and 128 is de-energized closing contacts D.R.3 and D.R.4. Line 131 which is joined to line 135 is now closed through contact D.R.3 to 137 and acts as one side of a

circuit to exhaust auxiliary valves 109 and 109A. The other side of this circuit line 130 being connected to line 134 is now closed with line 138 through D.R.4 and forms the other side of the line of the circuit to solenoid coils of valves 109 and 109A, thereby creating additional exhaust for air cells 58 and 58'. Expansion now of air cells 57 and 57' returns rocker means 9 to raised knife position. As previously stated, contacts 125 and 126 have been joined by connector bar of limit switch closing circuit between line 196(L.2) through C.R. relay 122 to line 192(L.1), thereby energizing C.R. relay and opening contacts 198(C.R.1) and 199(C.R.2). The opening of these contacts in turn breaks the circuit to relay 205(A.R.), dropping out contacts 204(A.R.1) and 223(A.R.2), and as contact 204(A.R.1) was a holding contact, relay 205(A.R.) is de-energized. Upon completion of the rocker means 9 action to raised knife position, limit switch 112 reverses in a snap action to close contacts 123 and 124 but as contact 204(A.R.1) is now open and in turn has opened contact 204(A.R.1) and contact 223(A.R.2), the circuit to relay 225(S.R.) has been interrupted. Consequently, contact 191(S.R.1) and contact 195(S.R.2) are now open and return rocker means 9 to raised knife position.

Simultaneously with the opening of contact 198(C.R.1) and contact 199(C.R.2) the circuit to line 206 is broken, and as the circuit was broken to relay 229(2.R.) its contact 230(2.R.1) was open and as contact 230(2.R.1) was a holding contact relay 229(2.R.) remains de-energized with the following results:

Contact 231(2.R.2) remains open and contact 230(2.R.1) remains open and contact 232(2.R.3) being a normally closed contact and is at the end of the stroke as aforementioned, limit switch 112 has reversed its action closing circuit between contacts 123 and 124, de-energizing relay 122(C.R.). Contact 199(C.R.2) is now re-closed, re-energizing line 206 which in turn energizes all lights 143d(1.L), 143c(2.L), 143b(3.L), 143a(4.L) and 143g(5.L). Closing of contact 231(2.R.2) as shown is in a counter circuit and is subject to the breaking of that circuit through contacts 191(S.R.1) and 195(S.R.2). Upon the energy being applied to the cutting action, as previously described, through the closing of contacts 191(S.R.1) and 195(S.R.2), this circuit had been closed and as contact 231(2.R.2) was closed counter 214b(2.C) recorded one cut of this dimension.

Thus, in the above description the presetting of the circuits for cutting a 24" width of panel was made and the actuation of the knife through the interruption of the light circuit and the preset circuits was described, and how the electrical energy of the control was used in actuating the air cells which in turn performed the mechanical action of cutting, and the reversing of the pressure and exhaust of the alternate air cells has been accomplished, causing the mechanical return of knife to original raised position, and the interruption of preset circuits in control panel, resetting control to original maximum cut dimension using all lights, and the counting of the cutting of a 24" piece has been recorded. The above, as stated, describes the mode of operation for a 24" cut using light 143c(2.L). If another dimension as 30" was desired, then light 143b(3.L) would be employed, and likewise, for the other lights, but the operation would be similar to that described for the 24" only using the different lights and different circuits.

Obviously, changes may be made in the form, arrangement and parts of my invention without departing from the principle thereof, the above setting forth only preferred exemplary forms of my invention.

I claim:

1. A pneumatic actuating mechanism comprising a pivotally mounted tool mounting rocker means; a fixed backing frame for said rocker means providing a variable spaced relation with said rocker means; expandable-collapsible air cells disposed oppositely between said rocker means and fixed backing frame providing during stroke a constant pressure and variable rotation force whereby is inherently provided a ratio of force required for the load; a bumper mounting rod fixedly mounted on said fixed backing frame; and a bumper means mounted on outer end of said rod whereby the arc of rotation of rocker means is controlled and rebound is provided to overcome air transfer lag and a force supplementing the air force is provided to change direction of rotation of rocker means.

2. A pneumatic actuating mechanism comprising a pivotally mounted tool mounting rocker means; a fixed backing frame for said rocker means providing a variable spaced relation with said rocker means; expandable-collapsible air cells disposed oppositely between said rocker means and fixed backing frame providing during stroke a constant pressure and variable rotation force whereby is inherently provided a ratio of force required for the load; a bumper mounting rod fixedly mounted on said fixed backing frame; and adjustable bumper means mounted on outer end of said rod whereby the arc of rotation of rocker means is controlled and rebound is provided to overcome air transfer lag and a force supplementing the air force is provided to change direction of rotation of rocker means.

3. A pneumatic actuating mechanism comprising a pivotally mounted tool mounting rocker means formed of a front and a back member disposed with respect to each other in the shape of a V; a fixed backing frame for said rocker means providing a variable spaced relation with said rocker means; an expandable-collapsible air cell disposed between said rocker means and fixed backing frame providing during stroke a constant pressure and variable rotation force whereby is inherently provided a ratio of force required for the load; actuating means operating alternately to said expandable-collapsible air cell to actuate said rocker means; a bumper disposed between the back member of the rocker means and the fixed frame whereby the degree of collapsing of the air cell on that side is controlled; and a second bumper disposed between the front member of the rocker means and the fixed frame whereby a safety protecting means is provided for the actuating means on that side of the rocker means.

4. A pneumatic actuating mechanism comprising a pivotally mounted tool mounting rocker means; a tool mounted on said rocker means; a fixed backing frame for said rocker means providing a variable spaced relation with said rocker means; an expandable-collapsible air cell disposed between said rocker means and fixed backing frame providing during stroke a constant pressure and variable rotation force whereby is inherently provided a ratio of force required for the load; means operating alternately to said expandable-collapsible air cell to actuate said rocker means; and a resilient curved material

product feed brake eccentrically mounted on said rocker means, engaging product being fed prior to tool contact and releasing product after clearance of tool from product.

5. A pneumatic actuating mechanism comprising a pivotally mounted tool mounting rocker means; a tool mounted on said rocker means; a fixed backing frame for said rocker means providing a variable spaced relation with said rocker means; an expandable-collapsible air cell disposed between said rocker means and fixed backing frame providing during stroke a constant pressure and variable rotation force whereby is inherently provided a ratio of force required for the load; means operating alternately to said expandable-collapsible air cell to actuate said rocker means; infeed belts for product being fed; a caterpillar type of chain feed angular bracket pivotally mounted on a cross shaft disposed on side of rocker means opposite to that of said tool; a caterpillar chain mounted on said bracket; sprocket means continuously driving said chain feed synchronously with said infeed belts; an arm fixedly eccentrically mounted on said rocker means having a slotted opening therein; a fixed rod carried by the caterpillar bracket, having a compression spring means disposed between said arm and the top surface of said caterpillar bracket; and an adjustment nut on said rod above said arm for positive control lift of said caterpillar bracket from the product being fed, whereby periodically said feed chain may be disengaged from said product.

6. A clipper mechanism comprising a pivotally mounted knife mounting rocker means; a fixed backing frame having its longitudinal axis parallel to and in spaced relation to the rotation axis of said rocker means providing a variable spaced relation with said rocker means; an expandable-collapsible air cell disposed between said rocker means and fixed backing frame providing during knife stroke a constant pressure and variable rotation force whereby is inherently provided a ratio of force required for the load; actuating means operating alternately to said expandable-collapsible air cell to actuate said rocker means; a bumper disposed between the back member of the rocker and the fixed frame whereby the degree of collapsing of the air cell on that side is controlled; and a second bumper disposed between the front member of the rocker means and the fixed frame whereby a safety protecting means is provided for the actuating means on that side of the rocker means.

7. A clipper mechanism comprising a pivotally mounted knife mounting rocker means formed of a front and back member disposed with respect to each other in the shape of a V; a fixed backing frame having its longitudinal axis parallel to and in spaced relation to the rotation axis of said rocker means providing a variable spaced relation with said rocker means; an expandable-collapsible air cell disposed between said rocker means and fixed backing frame providing during knife stroke a constant pressure and variable rotation force whereby is inherently provided a ratio of force required for the load; actuating means operating alternately to said expandable-collapsible air cell to actuate said rocker means; a bumper disposed between the back member of the rocker and the fixed frame whereby the degree of collapsing of the air cell on that side is controlled; and a second bumper disposed between the front member of the rocker means and the fixed frame whereby a safety pro-

pecting means is provided for the actuating means on that side of the rocker means.

8. A clipper mechanism comprising a pivotally mounted knife mounting rocker means formed of a front and back member disposed with respect to each other in the shape of a V; a fixed backing frame having its longitudinal axis parallel to and in spaced relation to the rotation axis of said rocker means providing a variable spaced relation with said rocker means; expandable-collapsible air cells disposed oppositely between said rocker means and fixed backing frame providing during stroke a constant pressure and variable rotation force whereby is inherently provided a ratio of force required for the load; and inlet and exhaust air control means, the exhaust exceeding in area the inlet means whereby back pressure resisting forces are reduced and rotational speed is increased with corresponding increase of impact to provide desired force.

9. A clipper mechanism comprising a pivotally mounted knife mounting rocker means formed of a front and back member disposed with respect to each other in the shape of a V; a fixed backing frame having its longitudinal axis parallel to and in spaced relation to the rotation axis of said rocker means providing a variable spaced relation with said rocker means; expandable-collapsible air cells disposed oppositely between said rocker means and fixed back frame providing during stroke a constant pressure and variable rotation force whereby is inherently provided a ratio of force required for the load; inlet and exhaust air control means, the exhaust exceeding in area the inlet means whereby back pressure resisting forces are reduced and rotational speed is increased with corresponding increase of impact to provide desired force; a bumper mounting rod fixedly mounted on said fixed backing frame; and a bumper means mounted on outer end of said rod whereby the arc of rotation of rocker means is controlled and rebound is provided to overcome air transfer leg and a force supplementing the air force is provided to change direction of rotation of rocker means.

10. A clipper mechanism comprising a pivotally mounted knife mounting rocker means; a knife mounted on said rocker means; a fixed backing frame for said rocker means providing a variable speed relation with said rocker means; an expandable-collapsible air cell disposed between said rocker means and fixed backing frame providing during stroke a constant pressure and variable rotation force whereby is inherently provided a ratio of force required for the load; means operating alternately to said expandable-collapsible air cell to actuate said rocker means; and a resilient curved product brake eccentrically mounted on said rocker means, engaging product being fed prior to knife contact and releasing product after clearance of knife from product.

11. A clipper mechanism comprising a pivotally mounted knife mounting rocker means; a knife mounted on said rocker means; a fixed backing frame for said rocker means providing a variable spaced relation with said rocker means; an expandable-collapsible air cell disposed between said rocker means and fixed backing frame providing during stroke a constant pressure and variable rotation force whereby is inherently provided a ratio of force required for the load; means operating alternately to said expandable-collapsible air cell to actuate said

21

rocker means; infeed belts for product being fed; a bellcrank lever arm pivotally mounted in spaced relation to said rocker means and on the side of said rocker means opposite to the side on which the knife is mounted; sprocket wheels mounted on said bellcrank arm; an endless feed chain mounted on said sprocket wheels continuously driven synchronously with said infeed belts; an arm fixedly eccentrically mounted on said rocker means; a fixed rod carried by said bellcrank lever arm having a compression spring means disposed between said eccentric arm and said bellcrank arm; and an adjustment nut on said rod above said eccentric arm for positive control lift of said endless chain from the product being fed, whereby periodically said feed chain may be disengaged from said product.

12. In a clipper mechanism, a pivotally mounted knife mounting rocker means; a fixed backing frame for said rocker means having a compressed air reservoir; and expandable-collapsible air cells communicatively connected to said air reservoir disposed between said rocker means and backing frame.

13. A clipper mechanism comprising a pivotally mounted knife mounting rocker means; a knife mounted on said rocker means; a fixed backing frame for said rocker means; an expandable-collapsible air cell disposed between said rocker means and fixed backing frame to actuate the rocker means in one direction; means operating alternately to said expandable-collapsible air cell to actuate said rocker means in the opposite direction; infeed belts for product being fed; resilient curved product brake mounted on said rocker means positioned to engage product being fed prior to knife contact and to release the product after clearance of knife from product and during releasing, giving an initial forward thrust to the product; a bellcrank lever arm pivotally mounted in spaced relation to said rocker means and on the side of said rocker means opposite to the side on which the knife is mounted; sprocket wheels mounted on said bellcrank arm; an endless feed chain mounted on said sprocket wheels continuously driven synchronously with said infeed belts; an arm fixedly eccentrically mounted on said rocker means; a fixed rod carried by said bellcrank lever arm having a compression spring means disposed between said eccentric arm and said bellcrank arm; and an adjustment nut on said rod above said eccentric arm for positive control lift of said endless chain from the product being fed, whereby periodically said feed chain may be disengaged from said product at a time when said resilient braking means engages the product and periodically depressed on the product after the resilient braking means has imparted a forward thrust to the product.

14. In a pneumatic actuating mechanism, the combination of a fixed backing frame comprising an air reservoir cylinder having two sub-tended converging plates; a rocker means pivotally mounted beneath said sub-tended plates having two upwardly diverging plates oppositely disposed with respect to said subtended plates; and hose air cells mounted between the sub-tended plates and the upwardly divergent plates, whereby is provided a backing frame characterized by its rigidity.

15. In a pneumatic actuating mechanism, the combination of a fixed backing frame comprising an air reservoir cylinder having two sub-tended converging plates; a rocker means pivotally

22

mounted beneath said sub-tended plates having two upwardly diverging plates oppositely disposed with respect to said sub-tended plates; and hose air cells of relatively small volume in comparison to said air reservoir mounted oppositely between the sub-tended plates and the upwardly diverging plates.

16. In a pneumatic actuating mechanism having a pivotally mounted rocker means comprising divergent plates; a fixed backing frame for said rocker means having two converging plates oppositely disposed with respect to said divergent plates of said rocker means and having the longitudinal axis of the intersection of said plates parallel to and in spaced relation to the rotational axis of said rocker means; and hose air cells mounted between the plates of said rocker means and said fixed backing frame.

17. In a pneumatic actuating mechanism, the combination of a fixed backing frame comprising an air reservoir cylinder having two sub-tended converging plates; a rocker means pivotally mounted beneath said sub-tended plates having two upwardly diverging plates oppositely disposed with respect to said subtended plates; an eccentrically mounted tool mounting means formed by being secured to one of said upwardly diverging plates; hose air cells mounted oppositely between the sub-tended plates and the upwardly diverging plates; and air conduits connecting said air reservoir cylinder and said hose air cells, whereby said tool mounting means is actuated by the periodic force of pneumatic pressure in said cells augmented by the lever advantage of said upwardly diverging plates and by its added weight eccentrically mounted.

18. In a pneumatic actuating mechanism the combination of a fixed backing frame comprising an air reservoir cylinder having two sub-tended converging plates; a rocker means pivotally mounted beneath said sub-tended plates having two upwardly diverging plates oppositely disposed with respect to said subtended plates; and a plurality of hose air cells mounted in spaced relation longitudinally of said rocker means, and on opposite sides of said rocker means between the sub-tended plates and the upwardly diverging plates, whereby localized air pressure means may be applied to said upwardly diverging plates.

19. In the combination of claim 17 and bumper means limiting the outward stroke of said upwardly diverging plate having the tool mounted means mounted thereon, whereby a rebound force is developed which overcomes lag in the pneumatic pressure for increased speed in reversing the movement of the rocker means.

20. The combination of claim 17 and air exhaust-to-atmosphere valves operatively disposed in said air conduits whereby the development of back pressure in the exhausting air cells is reduced.

21. A pneumatic actuating mechanism comprising a pivotally mounted rocker means comprising divergent plates; a fixed backing frame for said rocker means disposed adjacent said rocker means and comprising two divergent plates and having the longitudinal axis of the intersection of said plates parallel to and in spaced relation to the rotation axis of said rocker means; an air cell comprising a container formed of flexible substantially non-expandable wall construction, peripherally considered, mounted between said rocker means and fixed backing frame adapted to take the form created between the divergent wall of the fixed backing member and

the rocker means; and a knife mounting assembly fixedly secured to one plate of said rocker means, whereby said side of the rocker means is eccentrically loaded and whereby is provided a momentum of inertia which imparts a heavy cutting blow to the material being clipped.

22. In a pneumatic clipper actuating mechanism the combination of a fixed backing frame comprising an air reservoir cylinder having two sub-tended converging plates; a rocker means pivotally mounted beneath said sub-tended plates having two upwardly diverging plates oppositely disposed with respect to said sub-tended plates; an eccentric tool mounting means formed by being secured to one of said upwardly diverging plates; a cutting knife mounted in said tool mounting means; and a curved leaf spring brake means mounted on the side of said rocker means opposite to the tool mounting means adjusted to have its lowermost position pressing against and stopping the feeding of the material to be clipped just prior to the engagement of the knife with the material.

23. In a pneumatic actuating mechanism the combination of a frame; a pivotally mounted rocker means mounted on said frame; a fixed backing frame for said rocker means; an air cell comprising a container formed of flexible substantially non-expandable wall construction, peripherally considered, mounted between said rocker means and fixed backing frame; a bell

5 crank lever arm pivotally mounted adjacent one side of said rocker means on said frame; sprocket wheels mounted on said arm; feed chain mounted over said sprocket wheels; a spring leaf mounted adjacent the sprocket on one end of said arm and extending beneath the sprocket wheel mounted on the opposite end of said arm; and a lever arm mounted on said rocker means connecting said lever arm with said bellcrank lever arm, whereby the product being processed may be caused to lie flat while passing under said feed chain.

DONALD C. PORTER.
